UNITED STATES PATENT OFFICE

HERMAN G. MEYER, OF GREEN LAKE, WISCONSIN.

CALF-WEANER.

1,323,083.

Specification of Letters Patent.

Patented Nov. 25, 1919.

Application filed August 11, 1919. Serial No. 316,629.

To all whom it may concern:

Be it known that I, HERMAN G. MEYER, a citizen of the United States, residing at Green Lake, in the county of Green Lake and 5 State of Wisconsin, have invented certain new and useful Improvements in Calf-Weaners, of which the following is a specification.

This invention relates to weaners for 10 calves, cows and the like.

The object of the invention is to provide a simple device of this character which will effectively prevent and cure sucking, will not make the animal's nose sore, and in 15 which danger of loss is reduced to a minimum.

Another object is to so construct such a device that it will not interfere with grazing and requires no halter or other suspending 20 means for holding it in place.

Another object is to construct a simple, safe, sanitary and effective as well as humane weaner as it is possible to produce.

With the foregoing and other objects in 25 view, which will appear as the description proceeds, the invention resides in the combination and arrangement of parts and in the details of construction hereinafter described and claimed, it being understood that 30 changes in the precise embodiment of the invention herein disclosed may be made within the scope of what is claimed without departing from the spirit of the invention.

In the accompanying drawings:—

35 Figure 1 represents a perspective view of one form of this improved weaner shown applied,

Fig. 2 is a front elevation thereof,

Fig. 3 is a front elevation partly in section showing another form of the invention,

Fig. 4 is a front elevation of still another form, and

Fig. 5 is an end elevation of the form shown in Fig. 3.

45 In the embodiment illustrated in Figs. 1 and 2, the weaner 1 constituting this invention comprises a peg composed of two cones 2 and 3 with their larger ends arranged toward each other and connected by a shank 4 which is here shown integral with the cones, but may be separable if desired. This shank 4 is of a length slightly greater than

50 the thickness of the septum of a calf's nose and is designed to be passed through an aperture therein, shoulders 4' being formed at the ends of said shank to prevent the ac-

cidental disengagement of the device from the nose of the animal.

This peg is preferably composed of hard wood, although it may be composed of any other suitable material, or any combination of materials, and the apices of the cones 2 and 3 are sharpened to provide penetrating points 5 which are designed to prick the cow which the animal wearing it attempts 60 to suck, thus causing her to kick and prevent the accomplishment of the weaner wearing animal's purpose.

In the form shown in Figs. 3 and 5, the weaner 1^a is composed of two sections instead of being made integral as shown in Fig. 2 and is preferably constructed of metal, aluminum being preferred because of its lightness.

The cone-shaped section 2^a of this form 75 of the weaner is provided with a shank 4^a made integral with the larger end thereof with a rounded shoulder 6 at the base of said cone. This shank 4^a has an exteriorly threaded longitudinal extension 7 which is 80 designed to engage a threaded socket 8 carried by the base or larger end of the cone-shaped section 3^a, a washer 9 being preferably inserted in said socket to insure a reliable connection between the sections. 85

The sections 2^a and 3^a are provided intermediate of their ends with threaded portions 10, each having a groove 11 extending longitudinally through said threaded portion which is designed to register with a 90 similar groove 14 formed in a spur carrying member 12 shown clearly in Fig. 5, said grooves being designed to receive a cotter pin for holding member 12 engaged with the member carrying it. This member 12 95 is threaded for engagement with the threaded portion 10 of each section, it being understood, of course, that one of these devices 12 is provided for each section, and has a plurality of radiating spurs or prongs 100 13 which may be of any desired configuration and bent in any desired direction to adapt them to prick the leg or udder of the animal attempted to be sucked.

Flattened portions 15 are formed on the 105 sections 2^a and 3^a to facilitate engagement therewith of tools, used for handling the sections.

The form shown in Fig. 4 is similar to that shown in Figs. 3 and 5, except that the 110 detachable prong carrying elements 12 are omitted and the apices of the cone-shaped

sections 2^b and 3^b are provided with prongs or spurs 16 which flare outwardly and are preferably made integral with the sections. These sections also have cut-out or flattened portions 15^a for engagement by a pair of pliers or other suitable instrument, and at the bases of said sections rounded collars or shoulders 6^a are formed.

It is of course to be understood that the shanks 4, 4^a and 4^b must be made round and smooth and of material which will not injure the flesh of the animal in connection with which the device is to be used, since this shank is located in the aperture in the septum or partition between the nostrils of the animal. The shoulders at the ends of the shanks are also smoothed and rounded for a similar purpose.

In applying this device, after having tied the animal or secured it by a stanchion, a puncture is formed in the partition between the nostrils by a suitable sharp instrument, and the weaner is then inserted by passing it through said aperture until the shank is engaged therewith, the shoulders on the opposite ends of the shank operating to prevent longitudinal movement such as would be likely to disengage the device.

In the application of the sectional weaner, it is of course understood that the parts will be separated and the shank inserted through the animal's nose and then the other sections screwed into place.

This device, while being extremely simple, is easy to apply and cheap to manufacture, will be thoroughly effective, since any attempt made by the animal wearing it to suck another animal, will cause the penetrating elements carried by the device to prick the animal and cause resistance in addition to the strain which will be exerted by such an attempt on the nose of the animal wearing it.

Further, it may be said that the general object is to eliminate from that part of the weaner which rests in the animal's nose, any sharp edges that might cause inconvenience,

and all unnecessary sharp angles where mucus or feed might lodge and decay.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

Having thus fully described my invention, what I claim as new and desire to secure by Letters Patent, is:—

1. A calf weaner comprising a double cone-shaped peg with the larger ends of the cones extending toward each other and connected by a shank smaller in diameter than the bases of the cones, the free ends of the cones having penetrating points, and removable spur carrying elements carried by said peg.

2. A calf weaner comprising a double cone-shaped peg with the larger ends of the cones extending toward each other and connected by a shank smaller in diameter than the bases of the cones, the free ends of the cones having penetrating points.

3. A calf weaner comprising two elongated cone-shaped sections, one carrying a reduced longitudinally extending shank at its larger end, said shank having a threaded terminal, the other section having an internally threaded socket to receive the threaded portion of said shank, and penetrating elements carried by said sections.

In testimony whereof I affix my signature in presence of two witnesses.

HERMAN G. MEYER.
